6 Claims. (Cl. 62—84)

This invention relates to refrigeration systems, and more particularly to refrigeration systems employing staged compressors.

One problem frequently encountered in refrigeration systems of the compressor-condenser-evaporator type is that of removing compressor lubricant from the refrigerant. In staged compression systems it has been recognized that the interstage cooler serves as an efficient separator. However, since the cooler is not a lubricant purifier, it is necessary to treat the oil further (as by the application of heat) in order to remove the remaining refrigerant and render the oil suitable for re-use.

It is also known that the performance of staged refrigeration systems can be improved by cooling the low stage compressor. The art discloses many ways of cooling compressors but most require the use of expensive auxiliary equipment. Some, however, employ the refrigerant itself and simply allow a portion of the system charge to expand in the cooling jacket of the compressor. This method has met with some success but when used with rotary compressors of the vane type certain difficulties arise. The problem in this case is due to the fact that on shut-down, liquid refrigerant may condense in the cooling jacket, and on subsequent start-up this liquid vaporizes producing non-uniform cooling. As a result, seizure of the rotor frequently occurs.

The object of this invention is to provide a method and apparatus for simultaneously purifying the lubricant and cooling the low stage compressor in a satisfactory manner. According to this invention, the lubricant, or more correctly the lubricant-refrigerant mixture, separated in the cooler is transferred to the cooling jacket of the low stage compressor to maintain in that jacket a body of liquid in heat exchange relation with the compressor. The heat generated by operation of the compressor is transferred to the mixture in the jacket thereby driving the refrigerant from the lubricant and simultaneously cooling the compressor. The refrigerant so separated is transmitted from the jacket to the discharge flow from the low stage compressor and the purified lubricant is withdrawn and returned to the lubrication circuit.

The preferred embodiment of the invention will now be described in detail with reference to the accompanying drawings in which:

FIG. 1 is a schematic diagram showing a simplified refrigeration system incorporating the invention.

FIG. 2 is a sectional view taken on line 2—2 of FIG. 1.

As shown in the drawings, the refrigeration system includes a rotary low stage compressor 11 of the vane type having suction and discharge connections 12 and 13, and a high stage compressor 14 of the reciprocating piston type. The discharge connection 13 leads the compressed refrigerant from the low stage compressor through a trap 15 to an interstage cooler 16 whence it is delivered by a conduit 17 to the high stage compressor 14. The fully compressed refrigerant gas discharged by the high stage compressor 14 flows through a conduit 18 to a condenser 19 where it is liquified and discharged into a receiver 21. Liquid refrigerant is fed from receiver 21 to an evaporator 22 through a conventional expansion valve (not shown) and the vaporized refrigerant leaving the evaporator is returned to the suction connection 12 of the low stage compressor.

2

The interstage cooler 16 is of a conventional commercially available type and includes a horizontal tank 23 containing a perforated pipe 24 that communicates with connection 15 and is immersed in a bath 25 of liquid refrigerant. The apparatus for cooling the refrigerant bath is not illustrated. The refrigerant used in this system, for example ammonia, has a lower specific gravity than the lubricant, which is oil, and therefore, the oil separated from the refrigerant in cooler 16 collects in a vertical depending leg 26. Interstage cooler 16 may also be a vertical tank, in which case leg 26 is simply the bottom portion of the tank.

Associated with the low stage compressor 11 is a lubrication circuit including an oil reservoir 27 the top of which is connected to compressor suction conduit 12 by conduit 30 and which supplies oil pump 28, and branched conduits 29 and 31 that lead oil under pressure to the bearings, seal and other lubrication points of the compressor.

Compressor 11 is provided with a conventional cooling jacket 32 to which is connected a conduit 33 leading from the depending leg 26 of the cooler 16 or the bottom of a vertical cooler. The refrigerant-contaminated oil fed to the jacket 32 through conduit 33 is maintained in heat exchange relation with the compressor 11 with the result that the compressor is cooled. The heat absorbed by the mixture 34 in jacket 32 drives off the entrained refrigerant which rises to the top of the jacket and is returned to the interstage cooler 16 through conduit 35. The temperature of the refrigerant flowing through conduit 35 is indicative of the position of the liquid level 36 in jacket 32, and this level is maintained substantially constant by a thermostatically controlled valve 37 located in conduit 33. The thermometric bulb 38 connected with the valve actuator is fixed to conduit 35 and the actuating mechanism is so arranged that the valve 37 opens and closes as the temperature of the refrigerant in conduit 35 rises above and falls below a predetermined value. It will be understood that maintenance of a constant liquid level in jacket 32 affords a constant uniform compressor temperature.

The purified oil in jacket 32 has a higher specific gravity than the incoming contaminated oil and, therefore, it settles to the bottom of the jacket. This oil is withdrawn from the jacket and returned to reservoir 27 through a conduit 39. Flow through this conduit 39 is regulated by a second thermostatically controlled valve 41 that responds to the temperature in jacket 32 at a level above the connection with conduit 39. The temperature sensed by thermometric bulb 42 is indicative of the condition of the oil surrounding it inasmuch as the presence of vaporizing refrigerant at this level will lower the temperature of the bulb and the absence of such refrigerant will cause its temperature to rise. The valve 41 is set to open and close, respectively, as the temperature sensed by bulb 42 rises above and falls below a predetermined value selected to insure the presence of pure oil in the region around bulb 42. Since the conduit 39 withdraws oil from a point below the bulb, this arrangement guarantees that the oil conveyed to reservoir 27 is refrigerant free.

It sometimes happens, as a result of improper matching of refrigeration load to system capacity, that incomplete vaporization of refrigerant will occur in evaporator 22. This produces a condition commonly called "wet compression," i.e., liquid refrigerant is delivered to and expands in compressor 11. When this happens, the compressor 11 does not generate sufficient heat to purify the oil in jacket 32. As a safety measure, an auxiliary electrical heater 43 is installed in jacket 32 so that the purification process can continue during periods of "wet compression."

It should be mentioned that although cooling of the rotary compressor 11 is accomplished by evaporation of refrigerant in jacket 32, this will not adversely affect the compressor even during shut-down because of the presence of a substantial body of oil. The oil serves to disperse the refrigerant in the jacket 32, to reduce its evaporation rate and the rate of heat flow from the compressor and produce uniform temperature throughout the jacket.

As stated previously, the drawings and description relate only to a preferred embodiment of the invention. Since many changes can be made in the structure of this embodiment without departing from the inventive concept, the following claims should provide the sole measure of the scope of the invention.

What we claim is:

1. In a staged refrigeration system having a low stage compressor with a cooling jacket, a high stage compressor, a cooler arranged to cool the compressed gaseous refrigerant flowing from the low stage compressor to the high stage compressor, and a circuit for feeding lubricant to the low stage compressor, the method of separating lubricant from the refrigerant and cooling the low stage compressor which comprises

- (a) withdrawing from the cooler the mixture of lubricant and refrigerant that separates from the compressed gaseous refrigerant;
- (b) transferring the withdrawn mixture to the cooling jacket to maintain therein a quantity of this mixture in heat exchange relation with the compressor, whereby the refrigerant is driven from the mixture and the compressor is cooled;
- (c) removing the separated refrigerant gas from the cooling jacket and returning it to the compressed refrigerant in the cooler; and
- (d) removing the lubricant in the cooling jacket from which refrigerant has been separated and returning it to the lubricant circuit.

2. The method defined in claim 1 in which the rate of transfer of mixture from the cooler to the cooling jacket is controlled in direct relation to the temperature of the separated refrigerant gas removed from the jacket.

3. The method defined in claim 1 in which the lubricant has a higher specific gravity than the refrigerant; and in which the oil removed from the jacket is taken

from a point adjacent the bottom of the jacket when the temperature at a higher level in the jacket exceeds a predetermined value.

4. In a staged refrigeration system having a low stage compressor with a cooling jacket, a high stage compressor, an interstage cooler located in a discharge line leading from the low stage compressor for cooling the compressed gaseous refrigerant flowing to the high stage compressor, and a lubrication circuit for feeding lubricant to the low stage compressor, the combination of

- (a) a first conduit connecting the lubrication circuit with the cooling jacket at a point adjacent its bottom;
- (b) a second conduit connecting the cooling jacket with the cooler at a point adjacent its bottom;
- (c) a third conduit connecting the interstage cooler with the cooling jacket at a point adjacent its top;
- (d) first valve means controlling flow through the first conduit and shiftable in opening and closing directions; and
- (e) means responsive to the temperature of the liquid in the cooling jacket at a level above the connection with the first conduit for opening the first valve means when the temperature rises above a given value and for closing that valve means when the temperature falls below that value.

5. The combination defined in claim 4 including

- (a) second valve means controlling flow through the second conduit and shiftable in opening and closing directions; and
- (b) means responsive to the temperature in the third conduit for opening and closing the second valve means respectively as the temperature rises above and decreases below a certain value.

6. The combination defined in claim 5 including auxiliary means for heating the liquid in the cooling jacket.
